United States Patent Office

Des. 193,607

Patented Sept. 18, 1962

193,607

SOAP DISH

Thomas H. Ebbert, 214 Clifford Ave., Pittsburgh, Pa.

Filed Dec. 18, 1961, Ser. No. 67,939

Term of patent 14 years

(Cl. D4—3)

Fig. 1

Fig. 2

FIGURE 1 is an isometric view of a soap dish, showing my new design; and

FIGURE 2 is a top plan view thereof on the same scale as FIGURE 1.

The side and end not shown have substantially the same appearance as the side and end, respectively, as shown.

I claim:

The ornamental design for a soap dish, as shown and described.
